SAMUEL E. MCFARLAND, OF LONG BEACH, CALIFORNIA, ASSIGNOR TO AUTOMATIC RETRIEVING TROLLEY CORPORATION, OF LONG BEACH, CALIFORNIA, A CORPORATION OF CALIFORNIA.

AUTOMATIC RETRIEVING-TROLLEY.

1,157,630.

Specification of Letters Patent.

Patented Oct. 19, 1915.

Application filed June 1, 1912. Serial No. 701,094.

To all whom it may concern:

Be it known that I, SAMUEL EARL MCFARLAND, a citizen of the United States, residing at Long Beach, in the county of Los Angeles and State of California, have invented a new and useful Automatic Retrieving-Trolley, of which the following is a specification.

This invention relates to that class of electric trolleys adapted to automatically drop to lower the trolley wheel when such wheel is not restrained by the trolley wire, and which, by a down pull on the trolley rope, can be restored to position for returning the trolley wheel to the trolley wire.

The object of this invention is to provide a device of this kind having few parts and being of cheap and simple construction; that can be easily installed; that is simple and certain in operation and that can be easily adjusted to determine the length of upward movement of the trolley wheel after it has escaped from the wire.

The invention may be carried out in various forms, and various parts of the device may be variously located.

The accompanying drawings illustrate the invention in two of the forms in which it may be embodied.

Figure 1 is a side elevation partly in axial section on line x^1 , Figs. 2 and 3, of a trolley base with pole and trolley wheel thereon constructed in accordance with this invention; the operating position *a* being shown in solid lines; the tripping position *b* of the brace being shown in dotted lines; a depressed position *c* being shown in dash lines and the restoring position *d* of the resetting lever being shown in dot and dash lines. Fig. 2 is an enlarged sectional elevation from line x^2 , Fig. 1; the lower part of the standard being broken away. Fig. 3 is a like enlarged sectional elevation from line x^3 , Fig. 1, omitting the retrieving line. Fig. 4 is a sectional plan on line x^4 , Fig. 1. Fig. 5 is a fragmental elevation of the lower portion of another form of trolley constructed in accordance with this invention. Fig. 6 is an enlarged detail of the tripping

spring and its adjusting screw. Fig. 7 is 50 a sectional detail of the resetting knuckle joint.

Arrows on the section lines of the various views indicate the direction of sight.

The trolley comprises a standard 1; an 55 oscillating trolley pole which may be composed of the socket section 2 and pole proper 3 detachably and slidably seated in the socket section, said socket section being pivotally mounted on the standard by means of 60 the link 4 pivoted by pin 5 to the bent cramping clamp bar 6 which is pivoted to the upper end of the standard 1 by a transverse pin 7 on which is pivoted the clamp clip 8 through which is screwed the clamp 65 screw 9 to press the lower end of the trolley pole proper 3 to act in connection with link 4 and the clamp bar 6 to clamp the pole proper to the socket; also an oscillating extensible jointed brace comprising an air cylinder 10 with closed cap 11, a piston head 12 in the cylinder and a piston rod 13 for said head; the rod extending through the cap and pivotally connected, at its upper end by a pin 14, toggle-joint member 15, toggle-joint pin 16 and bracket 17, to the upper end of the socket section 2 of the trolley pole; the lower end of said brace being pivotally connected to the standard by the lower standard pin 18. The extensible member or rod 13 of said brace is provided with a shoulder 19 and with a spring 20 encircling the piston rod 13 and acting upon the cylinder cap 11, thus to yieldingly support the trolley pole when the toggle joint formed 75 by the rod 13 and toggle joint member 15 is in extended position, said member 15 being provided with a stop 21 arranged to engage the brace after the upper brace pivot 14 has passed the dead center and has risen above 80 a straight line drawn from center to center of the top and bottom pivots 16 and 18, so that when the brace is set the spring must be slightly compressed before the toggle joint can be bent to release the brace and 85 lower the pole. By this arrangement the brace is effective to sustain the trolley pole without danger of bending the toggle joint 90

95

and releasing the brace, so long as the force of the spring 20 is restrained by contact of the trolley wheel 22 with the trolley wire 23, or by any force sufficient to overcome the 5 spring and hold the brace against the stop 21.

An adjustable tripping spring 24 is fixed to the toggle-joint member 15 to press upon the piston rod with a tendency to bend the 10 toggle-joint formed by the toggle-joint member 15 and the rod. The force with which said spring acts may be regulated by the regulating screw 25 fixed to the member 15 and extending through a slot in the 15 spring and provided with a nut 26 to increase or decrease the tension of the spring.

Means are provided to move the toggle-joint member and the brace into the supporting position shown in solid lines in Fig. 20 1, in which figure said means consists in a resetting lever 27 pivotally mounted on the trolley pole by the top pin 16 and bracket 17 and provided with a shoulder 28 to act 25 upon the toggle-joint to move it into extended position shown in solid lines. Said resetting lever as shown is provided with an upwardly extending arm 29 carrying a pulley 30 around which is bent a line 31 fastened by one end at 32 to the upper end of 30 the trolley pole proper and having its other end led over a pulley 33 mounted on the trolley pole, and thence down as a trolley rope 34 to be handled by the conductor or other person wishing to retrieve the trolley.

35 Yielding means in the form of a spring 35 mounted on the top pin 16 and thus carried by the bracket 17 and the trolley pole, acts upon the resetting lever 27 to return it to the resting position shown in solid lines and 40 in the dot and dash lines in Fig. 1.

In practical operation of the device shown in Fig. 1, when the trolley wheel 22 rests against the trolley wire 23 the parts will be in the position shown in solid lines, the compressed spring 20 exerting its pressure to 45 force the trolley pole 3 upward and being held under compression between the cylinder cap 11 and piston rod shoulder 19 by reason of the pin 14 being above the dead 50 center plane of the lower standard pin 18 and toggle-joint 16. When the trolley wheel jumps from the trolley wire and is forced upward by the force of the spring 20, as indicated by the dotted position of the 55 trolley wheel, the consequent sudden upward movement of the trolley pole 3 swings downward the toggle-joint member 15 and the rod 13, the inertia of the swinging toggle-joint member and rod breaking the toggle joint; and the rod is retarded by the 60 suction in the cylinder, thus allowing the tripping spring 24 to aid in throwing the toggle-joint off center, thereby more quickly releasing it from its latched position, where- 65 upon the expansive force of the spring 20

continues to turn the toggle-joint member, thus allowing the weight of the trolley pole and its parts to lower the parts possibly to the position shown in dash lines, from which low position the spring 20 will then raise it 70 to a somewhat higher point of rest. Then the spring 20 may be compressed to raise the pole to again cause the trolley wheel to contact with the trolley wire by pulling on the trolley rope 34 to turn the lever 27 as 75 shown in dot and dash lines, so that the shoulder 28 will engage the toggle-joint member 15 as shown in dotted lines and turn the toggle-joint member to the latched position shown in solid lines. Then the trolley 80 rope may be paid out, whereupon the spring 35 acts to retract the resetting lever to the position shown in solid lines and the device is then capable of automatically repeating the foregoing operations in case the trolley 85 wheel again jumps from the trolley wire.

In the form shown in Fig. 5 the resetting lever 27' is provided at one end with the arm 29 and pulley 30 through which is rove the line 31 which is then roved through a 90 pulley 36 on the other end of the resetting lever, and thence roved through a pulley 37 fastened at the lower part of the trolley pole 3, and thence roved through a pulley 38 carried by an arm 39 of the resetting lever, 95 and thence finally to the trolley pole where it is made fast in any suitable manner, thus to increase the leverage that may be exerted to reset the toggle-joint member as hereinbefore set forth. The resetting lever 27' is 100 provided intermediately with an offset forming a shoulder 28' corresponding in function to the shoulder 28 of the resetting lever 27.

The operation of the form shown in Fig. 105 5 will be understood from the hereinbefore described operation of the form shown in Fig. 1.

The arm 29 of the resetting lever is preferably connected to said lever in the form of 110 a knuckle joint that is stopped at a right angle when in the resting position as shown in solid and dash lines in Fig. 1, and swings toward a straight extended position as the resetting operation is effected as shown in 11 the dot and dash lines in Fig. 1. The body of said arm is a channel iron as indicated in Fig. 7, and the end of the lever 27 is square to engage the web of the channel iron to form the stop and prevent the arm from 12 being drawn toward a dead center.

The standard is pivoted to the usual support 41 on the top of the car 42 by a vertical pin as indicated at 43. All the other pins are horizontal.

I claim:

1. A trolley comprising a standard, an oscillating trolley pole mounted on the standard, an oscillating extensible brace mounted on the standard, means to auto- 1

5 matically extend the brace, retarding means in opposition to the extending means, a toggle-joint member between the brace and the trolley pole, a stop to cause the toggle-joint to coöperate with the brace to support the pole in operative position, brace setting means to move the toggle member and brace into pole-supporting position, and yielding means to hold the setting means out of operative position.

70

10 2. A trolley comprising a trolley pole, a toggle-joint brace having an extensible member connected to the trolley pole, a spring on said member normally tending to extend said member, means operatable by sudden upward movement of the trolley pole to bend the toggle-joint to allow the trolley pole to swing downward, and a second spring bearing on the toggle-joint to aid 20 in bending it.

75

15 3. A trolley comprising a standard, a trolley pole pivoted to the standard, a jointed brace pivoted at one end to the standard and at the other end to the trolley pole and comprising means to force the trolley pole upward, and means only operatable by sudden upward movement of the trolley pole to 25 bend the brace joint.

80

20 4. A trolley comprising a standard, a trolley pole pivoted to the standard, a toggle jointed brace pivoted at one end to the standard, and at its other end to the trolley pole and comprising means to force the trolley pole upward, a stop to prevent bending 30 of the toggle-joint, means operatable by sudden upward movement of the trolley pole to straighten the toggle joint, and adjustable means tending to bend the toggle joint.

85

35 5. The combination with a trolley pole and a compressible spring to force the trolley pole upward, of a brace; a toggle-joint member pivotally connecting the pole and brace; means to prevent bending of the toggle-joint and a tripping spring fixed to the 40 toggle-joint member and pressing against the brace for the purpose set forth.

90

45 6. The combination with a trolley pole and a compressible spring to force the trolley pole upward, of a brace; a toggle-joint member pivotally connecting the pole and brace; means to prevent bending of the toggle-joint, a tripping spring fixed to the toggle-joint member and pressing against the brace; a regulating screw fixed to the 50 toggle-joint member and extending through a slot in the tripping spring and having a nut to change the tension of the tripping spring.

95

55 7. A trolley for a car comprising a trolley pole, an air cylinder, means pivotally connecting the pole and cylinder to the car, a piston to work in the cylinder and provided with a shoulder, a spring between the cylinder and shoulder, a toggle-joint member pivotally connecting the piston to the trolley pole, and provided with a stop, a

60 resetting lever arranged to operate the toggle-joint member to compress the spring, a spring to throw the resetting lever out of operating position, and means to operate the resetting lever.

100

8. A trolley comprising current conducting means, means to force the current conducting means upward, and piston means directly operatable by movement of the current conducting means to throw said forcing 75 means out of commission.

9. A trolley comprising current conducting means, means to force the current conducting means upward, and suction means directly operatable by movement of the current conducting means to throw said forcing 80 means out of commission.

10. A trolley comprising current conducting means, means to force the current conducting means upward, and fluid pressure 85 means directly operatable by movement of the current conducting means to throw said forcing means out of commission.

11. A trolley comprising current conducting means, means to force the current conducting means upward, and pressure means directly operatable by movement of the current conducting means to throw said forcing 90 means out of commission.

12. The combination with current conducting means, of means to force the current conducting means upward, and a piston directly operatable by the current conducting means to limit the upward movement of said forcing means.

95

13. A trolley comprising current conducting means, means to force the current conducting means upward, means to throw said forcing means out of commission, and a piston directly operatable by movement of the 105 current conducting means to operate said throwing means.

100

14. A trolley comprising standards, current conducting means mounted on the standards, a brace fastened to the current 110 conducting means, means slidably connecting the brace to the standards, and means operating to slide the brace through said connecting means to raise the current conducting means.

115

15. A trolley comprising standards, current conducting means mounted on the standards, a brace fastened to the current conducting means, means slidably connecting the brace to the standards, means operating 120 to slide the brace, and means to limit the sliding of the brace.

16. A trolley comprising standards, current conducting means mounted on the standards, a brace fastened to the current 125 conducting means, means slidably connecting the brace to the standards, means operating to slide the brace, and means to positively limit the sliding of the brace.

17. A trolley comprising standards, cur- 130

rent conducting means mounted on the standards, a jointed brace fastened to the current conducting means, means slidably connecting the brace to the standards, means operating to slide the brace, and resilient means to bend the brace.

In testimony whereof, I have hereunto set

Copies of this patent may be obtained for five cents each, by addressing the "Commissioner of Patents, Washington, D. C."

my hand at Los Angeles, California, this 25th day of May, 1912.

SAMUEL E. McFARLAND.
